OTTER BOARD

Donald Julius Groen, Surbiton, England

Application June 8, 1942, Serial No. 446,320
In Great Britain July 1, 1941

4 Claims. (Cl. 114—235)

This invention relates to improvements in otterboards and is particularly concerned with such devices for use in marine mine sweeping operations. An otterboard is used in side sweeping to extend a cable outwardly from the side of a ship and means are provided such as a float to prevent the cable from sinking. The tendency for the otterboard to move away from the side is due to the angle at which it is set to the direction of travel but this angle of incidence creates a drag which retards forward movement and if this angle is decreased to reduce the drag the force urging the board away from the ship is also reduced. It may be mentioned that on the magnitude of that force depends the length of cable which may be used as well as the position at which the board will ride with respect to the ship towing it, and hence the area which may be swept.

Now, an object of the present invention is to provide a more efficient otterboard which rides at a desirably small angle of incidence so that there is reduced drag and yet gives an increased force tending to move it away from the ship, so that either longer or more robust cables may be used therewith, or the board will ride at a more favourable position.

According to the present invention, the otterboard, which is preferably of streamline, aerofoil, curved or similar form in section seen in plan, has an overall height which is greater than its length.

To cause the board to ride at the desired small angle of incidence, the towing cable may be branched into, or attached to, three, four or more cables or chains which are secured to the board on one side thereof, either directly or through members projecting from the board, at points near the edges thereof, for example, at three points triangularly arranged, in the four corners of a rectangular board, or otherwise as may be convenient.

Further to ensure that the otterboard will ride upright as desired, the lower end thereof may be weighted.

The one end of the otterboard may be longer than the other providing always that the height be greater and preferably substantially greater than the length but it is further preferred that the board be symmetrically shaped on opposite sides of a line bisecting its major axis. In the latter case the length of the board may be decreased towards the top and bottom either by curving or inclining either the leading or the

trailing edge or by a combination of these possibilities.

In order that the invention may be clearly understood and readily carried into effect, three different constructional forms are by way of example more fully hereinafter described with reference to the accompanying drawings which are intended to be exemplary rather than definitive.

In these drawings:

10 Figure 1 is a side elevation of one form of otterboard,

Figure 2 is a rear elevation as seen from the left-hand side of Figure 1, and

15 Figure 3 is a plan view looking down on Figure 1.

Figures 4, 5 and 6 are views similar to Figures 1 to 3 of the same form of otterboard but having different means for the attachment of the towing cable.

20 Figure 7 is a side elevation of a modified form of otterboard, and

Figure 8 is a plan view of the otterboard of Figure 7.

25 Referring now to the said drawings throughout which like parts bear like reference numerals and with particular reference to Figures 1 to 3, the otterboard 1, seen in elevation, has the shape of an elongated rectangular parallelogram, whilst in section as may be seen from Figure 3 it

30 is of aerofoil or streamline shape. The exact construction of the board is not material to the present invention as it may be made of wood, or wood and metal, or entirely of metal. The trailing or narrow edge is conveniently reinforced

35 or protected by a metal overlay or reinforcement 2 which extends down on both sides. This edge is also protected by the provision of two or more projections 3 which serve as feet when the board is not in use and is standing on a ship's deck or other surface. The lower portion of the board is desirably similarly protected by a metallic overlay or reinforcement 4 which may also be arranged to give additional weight to that end of the board. The reinforcement 4 may be ar-

40 ranged to carry an additional weighting portion 5 arranged forwardly of the major axis so that most weight is in the region of the forward lower corner of the board.

On the one side of the board which is the 50 substantially flat side in the form of board illustrated, there is provided near each corner of the board a projecting element 6 which is conveniently given a streamline form as may be seen in Figure 1 which element has an aperture near its outer end within which is arranged a ring

1 to which may be connected a length of chain or cable 8 in any convenient manner, for example, by means of a holding device 9. The four chains or cables 8 are all connected to a ring 10 to which the towing cable (not shown) may be attached either directly or through the medium of a short length of chain 11 conveniently by means of a clamping device 12. The lengths of the chains or cables 8 may all be substantially the same although desirably the two chains or cables nearer the forward rounded edge are slightly shorter than the two chains or cables nearer the rear edge (as shown in the drawings) so that the point where the ends of the four chains or cables join the ring 10 is situated nearer to the front edge than the rear edge and substantially equidistantly from the top and bottom edges. In this way, the otterboard will always tend to ride with its rounded edge foremost in an upright position when, as may be clearly seen from Figure 1 of the drawings, its height preferably exceeds its length. The ratio of the height to the length may vary over wide limits but desirably the ratio is of the order of 2.3:1 to 5:1.

In Figures 4, 5 and 6, is illustrated an otterboard identical with that illustrated in Figures 1 to 3 but having different means for connecting a towing cable to the otterboard. In this case, the elements 6 are each replaced by a ring 13 to which is connected the end of a rod 14 as by bending around its end to form an eye 15. A similar eye is formed at the other end of each of the rods 14 and these four eyes are held together by means of a bolt 16 which extends through the limbs of a bifurcated connecting element 17 to which the towing cable (not shown) may be attached. In this case also the lengths of the rods 14 are substantially the same, although the front pair are preferably shorter apart from detail variations in length so that the eyes in the ends thereof will stack to be engaged by the bolt 16 as may be seen in Figure 5 and to position the connecting element 17 nearer to the front edge than the rear edge at a point substantially equidistantly spaced from top and bottom edges. When not in use, the connecting element 17 may be removed when the rods 14 may be collapsed to lie against the board.

Whilst in both of the foregoing examples the towing cable is indirectly connected to the board, in the one case through chains or cables 8 and projecting element 6 and in the other case through rods 14, the towing cable itself may be branched and directly attached to the board or to rings attached thereto. The points of connection are conveniently situated as far as possible from one another but the invention is not limited to four connection points since there may be three points of connection triangularly arranged as is later described with reference to a modified form of otterboard shown in Figures 7 and 8, or there may be more than four connection points say five in number, as may be most convenient having regard to the size of the board or the particular connection employed.

The otterboard shown in Figures 7 and 8 may be of similar general construction to the otterboards already described but is differentiated in the particular shape given thereto although it is also of aerofoil or streamline section as may be seen from the plan view shown in Figure 8. In this case, the board 21 is of diminishing length towards its top and bottom ends. The centre portion of the front edge 22 is straight and then

curves along the portion 23 to the apex and is similarly curved along the portion 24 to the base. The rear edge 25 is parallel to the corresponding portion of the front edge 22 and continues as a curved portions 26, 27 which match the curvature of the corresponding portions 23, 24 of the front edge but in opposite sense. The forward rounded portion of the board is protected by a metal reinforcement 28 whilst the rearward portion is similarly protected by a metal reinforcement 29. The lower part of the board is weighted by a weight 30 which is shaped to conform to the configuration of the board and an extra weight 31 is provided in a forward position at the lower portion corresponding in effect and purpose to the weight 5 already described. Three rings 32 in triangular arrangement are provided on the plane side of the board and the branched ends of the towing cable may be attached directly to the rings 32 or indirectly attached thereto through three chains, cables or rods corresponding to the cables or chains 8 and rods 14 already described, the arrangement in any case desirably being such that the point of divergence of the branched ends of the towing cable or of the auxiliary attachment means is situated forwardly along a line which bisects the major axis of the board. As in the previous example, the reinforcement 29 is provided with feet 3.

It will be appreciated from the foregoing examples that the board is desirably of symmetrical shape on opposite sides but its shapes are not limited to the examples above given since the forward edge may incline away from the mid point or be curved away from that point whilst the rear edge may be straight throughout its length or vice versa and although such an arrangement is preferred it is not essential since in some cases the length of the board may be greater at one end than at the other.

The arrangement for connecting the towing cable to the otterboard and the provision of extra weight at the lower portion of the board ensure that it will ride with its rounded edge facing forward and upright. The angle of incidence is determined by the respective lengths of the cable branches or the indirect attachment means and the arrangement is such that the board is arranged to ride at a minimum practical angle of incidence.

By causing the otterboard to ride at a lesser angle of incidence than is now customary, the drag set up by the device is reduced, but this does not reduce the force tending to move the device away from the ship since, due to the fact that its height exceeds its length and its preferred horizontal sectional shape, that force is increased or in other words the board has a greater lift. As the drag is reduced and the said force is increased, the otterboard may ride at a more favourable position in relation to the ship towing it, a longer towing cable may be used so that during mine sweeping operations a wider field may be swept, a more robust cable may be used, the towing operation carried out with a lesser expenditure of energy, or a combination of these possibilities to achieve greater efficiency.

70 I claim:

1. An otterboard of aerofoil section which has an overall height which is greater than its length, at least three projecting elements of stream-line form on one side of said board, to the ends of which elements are connected the ends of ele-

ments connected to a towing cable, means for weighting the lower portion of the board and additional weighting means for weighting the lower forward portion of the board.

2. An otterboard of aerofoil section which has an overall height which is greater than its length, at least three projecting elements of streamline form on one side of said board, chains connected to the ends of said elements, means for connecting the free ends of said chains and for connecting them to a towing cable, and means for weighting the lower portion of the board.

3. An otterboard of aerofoil section which has an overall height which is greater than its average length which is of diminishing extent in both directions away from the middle of the board,

connecting means leading from at least three points on the one side of said board, a towing connector common to all said connecting means, means for weighting the lower portion of said board, and additional means for weighting the lower end of the board forwardly of the major axis thereof.

4. An otterboard of aerofoil section having an overall height greater than its length, at least three attaching devices on one side of the board to which elements are attached to receive the connection of a towing cable, and a plurality of weighting means at the lower portion of the board, with one of said weighting means wholly forward of the major axis of the board.

DONALD JULIUS GROEN.
